UNITED STATES PATENT OFFICE

171,630

DESK

Herbert Paul Zimmermann, Amityville, N. Y., assignor to The General Fireproofing Company, Youngstown, Ohio, a corporation of Ohio

Application September 2, 1952, Serial No. 21,279

Term of patent 14 years

(Cl. D33—7)

To all whom it may concern:

Be it known that I, Herbert Paul Zimmermann, a citizen of the United States, residing at Amityville, in the county of Suffolk and State of New York, have invented a new, original, and ornamental Design for a Desk, of which the following is a specification, reference being had to the accompanying drawing, forming part thereof.

Figure 1 is a front elevation of a desk showing my new design.

Figure 2 is a rear elevation thereof.

Figure 3 is a side elevation of the desk shown in Figures 1 and 2.

Figure 4 is a perspective view thereof.

Figure 5 is an enlarged fragmentary perspective view thereof;

Figure 6 is an enlarged fragmentary elevational view illustrating the profile of the edge of the top;

Figure 7 is an enlarged perspective view of one of the drawer pulls shown in Figure 1.

Figure 8 is a plan view of the desk top.

The characteristic features of my design for the desk shown reside in the provision of wide sweeping curved surfaces connecting the narrow flat front pedestal faces with the flat side faces at the opposite outside front corners and also at the corners of the knee-hole side portions.

I claim:

The ornamental design for a desk, as shown and described.

HERBERT PAUL ZIMMERMANN.
